UNITED STATES PATENT OFFICE.

HENRY F. FREISE, OF OLD MONROE, MISSOURI.

CORN-HUSKING MACHINE.

Application filed October 6, 1926. Serial No. 139,834.

My invention has relation to improvement in corn husking machines, and it consists in the novel features of construction more fully set forth in the specification and pointed out 5 in the claims.

The object of the invention is to provide a machine that will break the ear from the stalk and remove the shucks therefrom as the ear passes through the machine. A further object is to provide a corn husking machine that is simple and composed of comparatively few parts so as to not readily get out of order. Further and other advantages will be better apparent from a detailed description of the invention in connection with 15 the accompanying drawings, in which—

Figure 1 is a top plan of my improved machine with parts broken away; Fig. 2 is a side elevation thereof; Fig. 3 is a vertical 20 sectional detail taken on the line 3—3 of Fig. 1; Fig. 4 is a detail view of the upper end of the husking rollers showing how they are mounted and driven; Figs. 5, 6 and 7 are top plan diagrams showing three successive 25 positions of the ear of corn in the machine; Fig. 8 is a side elevation with the parts in a position corresponding with that in Fig. 5, before the ear has been engaged by the crank; and Fig. 9 is a similar view 30 showing the crank moved to raise the ear so that it will be gripped between breaking roller and abutment block.

Referring to the drawings, 1 represents a sledge on which is mounted a steel framework 2 provided with a table, or platform 3 composed of sections *a*, *b* between which is a slot 4 having a flaring mouth 5. The section *a* is fixed on the framework 2, but the section *b* is hinged thereto so that it may 35 be raised in order to permit access to the machinery below the table.

A counter-shaft 6 is mounted in bearings 7, 7 secured to opposite angle braces 8, 8 of the framework, said counter-shaft having a pulley 9 on one end adapted to be connected by a belt 10 to drive pulley 11 of an engine 45 12 rigidly secured to the sledge 11.

A cylindrical abutment block 13 is fixed to the underside of section *a* of the table 3, adjacent to the slot 4, said block being traversed by a vertically disposed shaft 14 mounted in bearings 15 and 16 mounted respectively in the table and sledge. A crank 17 is fixed on the shaft 14 immediately below the block 13 and a spindle 18 projects upwardly from the free end of said crank, 50

said spindle having a roller 19 loosely mounted for rotation upon it. A worm wheel 20 is fixed on the shaft 14 just below the crank 17, and a worm 21 is fixed on shaft 6 60 in a position to mesh with wheel 20, whereupon the crank 17 will be revolved around the block 13 on imparting motion to the shaft 6 by means of engine 12. A toothed dog 22 is pivotally secured on the underside of section *b* of table 3 just about opposite the block 13, said dog being urged to project slightly beyond the adjacent edge of the slot 4 by a string 23, the movement of the dog toward the slot being limited by a stop 70 pin 24.

With the crank 17 revolving (about 60 R. P. M.) as above described, if a stalk of corn is drawn backward over the table 3 so that one of the ears falls into the slot 4, said 75 ear will hang down in the path of the crank 17 (see Figs. 5 and 8) which will strike the ear, tilting it upward (Figs. 6 and 9) so that the revolving roller 19 will warp the ear around the block 13 (Fig. 7) until it breaks 80 from the stalk. The stalk is held in place during the above operation by the operator and is prevented from yielding, under the pull exerted by the crank 17, by the dog 22 which grips the shuck near the point where 85 the ear is attached to the stalk. The co-operation of the dog also assists in tearing the shuck from the ear, although often the shuck remains on the ear after it is broken from the stalk. In order to entirely remove the 90 shucks from the ear suitable shucking mechanism is provided.

Two pairs of rollers 25, 26, 25, 26 are arranged with their upper ends below and on either side of the crank 17, said rollers being 95 inclined downwardly to a chute 42. The rollers 25 of each pair have spines 27 projecting from their surfaces, and the rollers 26 have complementary depressions 28 for receiving said spines. At their upper ends 100 the rollers 25, 26 are provided with spindles 29, 30 respectively mounted for rotation in bearings 31, 32 fixed on a supporting angle iron 33, and at their lower ends the rollers have spindles 34, 35 mounted in bearing 105 brackets 36, 37 respectively. A pair of pinions 38, 39 are mounted on spindles 29, 30 of each pair of rollers 25, 26 respectively, and bevel pinions 40, 40 are mounted on the upper ends of spindles 29, 30, the pinions 110 40, 40 meshing with bevel gears 41, 41 fixed on the counter-shaft 6, so that when said

shaft is rotated (as heretofore described), the rollers 25 of one pair and rollers 26 of the other pair will be rotated. As the rollers 25, 26 of each pair are connected by the 5 pinions 38, 39 said rollers 25, 26 will be rotated toward each other, the spines 27 of rollers 25 entering the depressions 28 of rollers 26 as said rollers rotate.

If an ear of corn is broken from the stalk 10 without being shorn of its shucks, it will fall through the hopper H and land upon one or the other of the pairs of rollers just described, adjusting itself longitudinally of the rollers, whereupon the spines of one roller 15 will cooperate with the depressions of the other roller to tear the shucks from the ear, said shucks being discharged downwardly between the rollers, and the ear traveling the length of the rollers ultimately to discharge from the chute 42. In order to guide the ear of corn as it falls from the breaking-crank, a V shaped apron 43 is disposed between the pairs of rollers.

The shucking rollers 25, 26 are already in use in corn shucking machines, and I make no claim to said shucking rollers except in combination with the mechanism that I employ for breaking the corn from the stalk.

In order that the sledge 1 may be easily moved in the course of the corn husking operation, I provide a drum 44 loosely mounted on the shaft 14, said roller being capable of connection with the shaft by means of the clutch members 45, 46 of a clutch, the member 45 being feathered on the shaft 14, and operated into and out of engagement with the member 46 fixed to drum 44 by means of a shift lever 47. A rope 48 has one end secured to the drum 44 while the other end may be connected to any fixed support, such as a tree, whereupon, when the drum 44 is rotated, the rope 48 will be wound thereon and the sledge 1 dragged to a new location.

Having described my invention I claim:

1. A corn husking machine comprising a platform, said platform having a slot, pro-

vided with a flaring mouth, an abutment block fixed beneath the platform and adjacent to said slot, a crank-arm disposed below said block, and a roller vertically disposed on the free end of the crank-arm, means for revolving said roller about the block, the said slot in the platform being adapted to receive an ear of corn as the stalk is disposed on the platform, means for holding the stalk in place when the crank is rotated to lift the ear of corn to a position so that the roller will warp said ear over the abutment, thereby breaking the ear from the stalk. 55

2. In a corn husking machine, the combination of a corn breaking and a husking device, the breaking device comprising relatively fixed and movable members, said movable member being adapted for rotation about the fixed member, the husking device comprising oppositely rotating rollers having formations adapted to tear the shucks from the corn, means for guiding the detached corn to the husking rollers, and means including a source of motive power for actuating the breaking and husking devices. 60

3. In a corn husking machine, a work platform having a slot adapted to receive the depending ear of corn when the stalk is placed on said platform, an abutment block beneath said platform and adjacent to said slot, a shaft disposed on the vertical axis of said block, a crank fixed on said shaft immediately below said block, a roller mounted on the end of said crank and having its vertical axis parallel to that of the block, said roller being revolved about the block and operating to warp the ear of corn over the block to break it from the stalk on imparting motion to the shaft, means for holding the stalk while the ear is being detached therefrom, and means for actuating the shaft. 70

In testimony whereof I hereunto affix my signature.

HENRY F. FREISE.
